UNITED STATES PATENT OFFICE.

JOHN D. TIEKEN, OF PIPER CITY, ILLINOIS.

CURTAIN-HOLDER.

SPECIFICATION forming part of Letters Patent No. 758,570, dated April 26, 1904.

Application filed August 21, 1903. Serial No. 170,350. (No model.)

To all whom it may concern:

Be it known that I, JOHN D. TIEKEN, a citizen of the United States, residing at Piper City, in the county of Ford and State of Illinois, have 5 invented certain new and useful Improvements in Curtain-Holders; and I do hereby declare the following to be a full, clear, and exact description of the invention, such as will enable others skilled in the art to which it appertains 10 to make and use the same.

My invention relates to improvements in curtains more particularly adapted for use on carriages, especially for the backs of buggies and like vehicles.

15 It has for its object to provide a curtain adapted for this use which can easily be raised or lowered and can be quickly and securely fastened in its raised position.

The invention consists in providing a preferably weighted rod at the bottom edge of the curtain, upon which said curtain can be rolled as it is raised, said rod having a pair of spring-fingers forming a catch at each end adapted to engage a knot or knob on a cord secured 25 to the top of the window-frame, whereby the curtain may be held in its raised position.

In the accompanying drawings, illustrating the preferred embodiment of my invention, Figure 1 is a view of a back of a buggy-top, 30 with the curtain down. Fig. 2 is a view of the upper part of the frame with the curtain up; and Fig. 3 is a view of the rod, showing the catches.

Referring more particularly to the drawings, 1 is the buggy-top, 2 is the curtain, and 3 is the rod, which is suitably secured to the lower edge of said curtain. The curtain is fastened at the top to the frame in any suitable and convenient manner—such as rivets, stitching, &c.—and in raising it rolls upon the rod, as is quite common. To each end of the rod, which is preferably of metal or weighted material, is suitably secured by rivets or otherwise a pair of oppositely-curved spring-fingers 4, forming a catch. Each pair of these fingers may be made of one piece of spring-steel bent at the center, where it is secured to the end of the rod, making a loop 5, coming together near their ends at 6, with the extremities curved away from each other, as at 7, to

act as a guide. At each end of the top of the frame is secured a short cord 8, carrying at its end a knob 9, preferably of metal. The curtain is raised by rolling it upon the rod, and when it reaches the top the cords are 55 slipped into the catches 4 at its ends, the knobs 9 retaining said rod with the curtain in its raised position. The cords should be just long enough to permit of being slipped into the catches above the knobs when the curtain is 60 completely wound up, so that said curtain will be retained in that position. The frame may also be provided with another pair of these cords near its bottom, which may be used to fasten the curtain down. Ordinarily, how- 65 ever, the weight of the rod is sufficient.

I do not limit myself to the specific form of construction of catch on the end of the rod, as each may be made of two separate pieces secured at opposite sides of said rod, or their construction may be varied in many other ways. Also in place of knobs on the cord a mere knot will suffice, and the cords themselves may be replaced by metal rods hinged, pivoted, or otherwise hung and having enlarged portions 75 or knobs on their ends. I therefore do not limit myself to the details of construction herein described, as they may be changed at will and the spirit of my invention remain intact and be protected. 80

Having thus described my invention, what I claim as new, and desire to secure by Letters Patent, is—

1. In a device of the character described a curtain having its upper edge suitably fastened 85 to the frame, a rod adapted to hang at the bottom of said curtain and upon which said curtain is adapted to be rolled, spring-loops on the ends of said rod and pendants secured at the upper portion of said frame having knobs 90 adapted to engage said loops.

2. In a device of the character described a curtain having its upper edge suitably fastened to the frame, a rod adapted to hang at the bottom of said curtain and upon which said curtain is adapted to be rolled, spring-loops on the end of said rod and cords secured at the upper portion of said frame having knobs 95 adapted to engage said loops.

3. In a device of the character described a 100

- curtain having its upper edge suitably fastened to the frame, a rod adapted to hang at the bottom of said curtain and upon which said curtain is adapted to be rolled, a pair of spring-fingers forming a loop attached to the ends of said rod and pendants secured at the upper portion of said frame having knobs adapted to engage said loops.
4. In a device of the character described a curtain having its upper edge suitably fastened to the frame, a rod adapted to hang at the bottom of said curtain and upon which said cur-

tain is adapted to be rolled, a pair of spring-fingers forming a loop attached to the ends of said rod and cords secured at the upper portion of said frame having knobs adapted to engage said loops. 15

In testimony whereof I affix my signature in presence of two witnesses.

J. D. TIEKEN.
